KNITTING MACHINE

Edward H. Steere, Asheboro, N. C., assignor of
one-half to Chisolm C. Cranford, Asheboro,
N. C.

Application February 5, 1935, Serial No. 5,122

4 Claims.

(Cl. 66—8)

The present invention relates particularly to circular knitting machines and has as its main object to speed up production by means of a plural yarn feed and at the same time to eliminate undesirable circumferential striping which sometimes occurs as the result of non-uniformity in the yarn where a single yarn is knit.

In addition to mechanism for effecting the additional yarn feed, the invention includes means for effecting tuck stitching at the main knitting station, the right hand stitch cam for this purpose being mounted independently of the left hand stitch cam and being independently movable out of the range of the needle butts.

The invention also includes a method and a fabric.

For the purpose of illustrating the invention I have shown it in the accompanying drawings as applied to the well known Scott and Williams Model K machine, designed for knitting turned welt stockings. I shall give herein only a general description of the basic machine in view of the fact that those skilled in the art are fully familiar therewith. Reference may also be had to Scott and Williams Patents No. 1,148,055, July 27, 1915 and No. 1,282,958, October 29, 1918. Also a discussion of the Model K machine will be found in "American Knitting Machines" by Metcalf, Textile American Publishing Company, Boston, 1928.

It is pointed out that the invention is by no means confined in application to this particular machine, since it may be used in conjunction with knitting machines of other types.

In the accompanying drawings:

Figure 1 is an elevation of the head of the said Model K machine with the present invention applied thereto.

Figure 2 is a plan view of the head of Figure 1 with certain super-structure removed in order to reveal underlying devices.

Figure 3 is a section substantially on line 3—3 of Figure 1.

Figure 4 is a section substantially on line 4—4 of Figure 2.

Figure 5 is a bottom view of the sinker cam as modified by the present invention.

Figure 6 is a plan view of the transfer cap and associated devices.

Figure 7 is an elevation of the transfer cap and associated devices as seen from the right of Figure 6.

Figure 8 is a section substantially on line 8—8 of Figure 5.

Figure 9 is a section substantially on line 9—9 of Figure 5.

Figure 10 is a view taken substantially on line 10—10 of Figure 2 or line 10—10 of Figure 4.

Figure 11 is a plan view, partly broken away, 5 of an auxiliary needle cam mechanism in accordance with the present invention.

Figure 12 is a view similar to Figure 11 with the cams proper removed in order to disclose their supporting means.

10

Figure 13 is a developed view of the needle cam cylinder and associated cams including those added by the present invention.

Figure 14 is an elevation of the knitting head with another modified form of the invention applied thereto.

15

Figure 15 is a section substantially on line 15—15 of Figure 14, with parts omitted.

Figure 16 is a plan view of the head as in Figure 14, with parts omitted.

20

Figure 17 shows in elevation a pair of drum cam follower levers which appear also in Figure 14.

Figure 18 is an elevation of a drum cam designed for cooperation with the follower levers of 25 Figure 17, and

Figure 19 is a fragmentary view, greatly enlarged, of a fabric produced in accordance with the present invention.

Referring to the drawings, reference numeral 30 20 designates a circular fixed bed plate which rotatably supports a bevel gear 21, Figure 4, on a vertical axis, the gear having a central opening whose margins are surmounted by an upwardly extending cylindrical sleeve 22 integral with the 35 gear. Needles 23 are slidable in vertical grooves of a needle cylinder 24 which is keyed to sleeve 22. The needles may have long, short, and intermediate butts, but in any event there is at least a group of needles with butts shorter than those 40 of another group. For a purpose to be herein-after described, there are also provided two needles with extra short butts in the group of shorter butt needles.

The needle cylinder carries at its upper end a 45 sinker ring 25 upon which floats a sinker cam ring 26, the latter ring being held down on the former by means of clips as at 27, Figure 1. Ring 26 carries a pair of spaced lugs 28 and 29 in which are mounted adjustable abutment screws 30 and 31 which coact with an upright post 32 mounted on the bed plate. During circular knitting, abutment 30 engages the post, while during reciprocation of the needle cylinder abutments 30 and 31 will alternately strike the post, there being

50

55

sufficient friction between the rings 25 and 26 so that the former tends to carry the latter with it.

A standard 33 has pivoted thereto a latch guard ring 34, the latter having a lug 35 opposite its 5 pivot point normally resting on the top of post 32. A bracket 36 mounted on ring 34 rotatably supports a vertical shaft 37 coaxial with the needle cylinder, shaft 37 carrying at its lower end the transfer dial 38. Drive for shaft 37 is derived 10 from a parallel shaft 39 journaled adjacent the edge of plate 20 and connected to shaft 37 through a horizontal shaft 40 and bevel gearing including the gears 41 and 42, Figure 1. The transfer dial is driven at the same speed as the needle cylinder 15 and sinker ring.

Mounted on a pin 43 supported in a yoke 43' in connection with ring 34, are a number of yarn feeding fingers 44. While the usual equipment of the machine includes five of these fingers, I 20 have shown only four in Figure 2, one having been removed in order that its associated push rod 45, Figure 1, may be utilized for a purpose to be hereinafter described.

The pattern drum is shown at 47 and the pattern chain, which controls the racking of the drum in the well known manner, at 48. The chain sprocket is shown at 48', and drum driving gears at 41a, 41b and 41c.

The needle cam cylinder 49, Figures 4 and 13, 30 is of usual design except that just beyond the cam rise 50 it is provided with a top recess 51. Associated with the needle cylinder cam are the right and left hand stitch cams 52 and 53, and reference numerals 54 and 55 designate the upper 35 picks. Upper and lower central cams are shown at 56 and 57, an anti-run-back cam at 58, and dividing cam portions at 59. The jacks are designated at 60, the jack cam at 60', a group of short butt needles at 61 and of long butt needles at 62, 40 Figure 13, reference numerals 63 and 64 designating two needles with butts shorter than the butts of the short butt needles and spaced a number of needles apart in the short butt group.

Ordinarily the stitch cams are mounted on a 45 semi-cylindrical collar which is slidable toward and away from the needle cylinder to bring the stitch cams into and out of action. According to the present invention, each of the stitch cams is mounted on a quarter cylindrical segment and 50 that which supports the left hand cam may be fixed. The segment 65 which supports the right hand stitch cam is slidable on the bed plate and has a bottom key engaged in a radial slot 66 in the bed plate, Figure 3, and an outer bottom 55 flange 65', provided with a slot 67, Figure 3, in which is engaged a guide screw 68. By mechanism to be hereinafter described, the segment 65 may be moved outwardly so that the right hand stitch cam will not affect the course of the 60 jackless needles and the same will pass without doffing the stitch, thereby making tuck stitches.

According to the present invention two auxiliary knitting stations are provided, so that three yarns are knit in for each revolution of the needle cylinder. At each auxiliary station there is provided a lifting and a lowering cam, the latter being a stitch cam, and auxiliary sinker cams. Yarn feeding means is provided at each station and a single clamp and cutter device is provided 65 for the two auxiliary stations.

While the number of auxiliary stations may be varied, I have found that the most satisfactory results may be obtained with two, as herein disclosed. With only one, the decrease in striping effect due to variation of the yarn is not adequate 75

and with more than two auxiliary stations the courses in an article such as a stocking may take too steep a spiral so that the fabric is apt to pull on a basis. With a main and two auxiliary stations, the knitting is, of course, three times as fast as with a single main station and any striping effect is successfully avoided.

The gap closer 69 has a horizontal flange over which is engaged the horizontal arm of a clip 70, Figure 4, the clip having a vertical arm secured 1 by means of a screw to the latch guard ring 34, the horizontal arm serving to hold down the gap closer. Clip 70 serves as a convenient means for the support of a vertical stud 71 longitudinally of which is slidable an arcuate bar 72. An arm 1 73 is fixed in outwardly projecting relation on top of bar 72 and stud 71 passes through this arm as well as through the bar, so that an extended bearing surface is provided. An outwardly projecting lug 74 on bar 72 is apertured to receive 2 an upright stud 75 whose lower end is received in a bore in the latch guard ring. Stud 75 has a stop collar 76 adjustable thereon and a tension spring 77 surrounds stud 71 with its lower end anchored to arm 73 and its upper end secured to 2 the top portion of the stud. The spring tends to lift arm 73 and bar 72, this tendency being limitable by the stop collar 76.

On its inner arcuate surface bar 72 has secured thereto, by means of screws 78 and 79, a pair of vertically extending yarn feeding fingers 80 and 81 which project considerably below the bar. The fingers 80 and 81 seat in vertical grooves in bar 72 and have longitudinally extending slots 80a and 81a through which the attaching screws are passed. By reason of the slots, the fingers may be adjusted vertically relative to bar 72 so that the yarns x and y engaged in eyes 80b and 81b in their lower ends, Figure 10, may be moved between accurate feeding and non-feeding positions as the result of vertical adjustment of bar 72. Spring 77 acts to lift the yarn above the needles so that it will not be caught by the latter.

Mounted on the right hand end of pin 43, Figure 2, is a barrel 82 which carries an arm 83 curved above the transfer cap in a manner to avoid interference with the other mechanisms and to bring its end 84 above bar 72 and adjacent arm 73. Barrel 82 has also fixed thereto an oppositely extending arm 85 curved to bring its extremity 86 above a vertically reciprocable bar 87, whose upper end is guided in a slot in a clip 88 secured to the standard 33. The push rod 45 is provided with a substantially vertically extending narrow recess 89 in its outer edge which receives the lower end of bar 87 and the push rod is engageable by cams 90 and 91 lying in the same vertical plane on drum 47. When push rod 45 is lifted by one of these cams, bar 87 participates in its movement and thus rotates barrel 82 in a clockwise direction, as in Figure 2, depressing arm 83 and thereby lowering bar 72 and the fingers so that the yarn is brought down to a position to be taken by the needles. It will be noted that the arm end 84 is adjacent the point of attachment of spring 77 to bar 72 and due to this arrangement any tendency for the slide to bind on the guide studs is avoided. A torsion spring 83' tends to lift arm 83, the effect of the spring being limited by push rod 45 and arm 83 in turn ordinarily limiting the effect of spring 77.

The extra yarns in the present embodiment are thrown in only when plain circular knitting is to be done and herein are intended to be fed when knitting the leg and foot of the stocking. Cam 90

is arranged on drum 47 so as to insure the feeding of the extra yarns while the leg is being knit and cam 91 is arranged to control the extra yarns in knitting the foot.

5 Mounted on the transfer cap are the usual spring guide finger 92, the clamp 93, and the cutter 94, these being at the main knitting station. I have modified the usual operating lever 95 for the clamp and cutter by forking it at its free 10 end to provide the two arms 96 and 97, the arm 96 being connected by means of an operating link with the clamp and cutter 93, 94 and the arm 97 being connected by means of an operating link 98 with a clamp and cutter for the yarns fed 15 by the fingers 80 and 81.

Referring particularly to Figures 6 and 7, a post 99 has its lower end fixed in the fixed top plate of the transfer cap 38' and its upper end received in an aperture in bracket 36, the post 20 being fixed against turning. Adjacent the post a cutter blade 100 is fixed on the top plate and carries a cooperating blade 101 pivoted thereto on a screw 100'. Blade 101 has a tail portion which is bent and pierced to receive the lower 25 horizontally bent end of link 98. The upper end of link 98 is threaded in a small block 98a, Figure 2, pivoted to arm 97 by means of a screw 98b. A clamp 102 has a sleeve portion 103 slideable on post 99 and urged downwardly by a compression 30 spring 104 interposed between the sleeve portion and bracket 36. Post 99 has a longitudinal groove in which is engaged the inner end of a screw 105 fixed in collar portion 103 so that 35 the clamp is held against turning about the axis of the post. The clamp carries a rigid pin 106 which projects above blade 101 and engages the upper edge thereof. Lever 95 is spring-influenced in such a manner that downward pressure is exerted on link 98 so that the cutter blades are normally closed and the foot of the clamp engages the top of the transfer cap. In Figure 7 the 40 blades are shown as open and the clamp as lifted. A spring yarn guide clip 107 is positioned on the opposite side of clamp 102 from the cutter, the top plate of the transfer cap being cut away and beveled as at 108 and the sub-plate portion being beveled as at 109 so as not to obstruct the yarn. As here shown, the fixed blade 100 is at one end 45 of an angle strip whose other end 110 is secured against a fixed hub 111.

A push rod 112, Figure 1, has its upper end disposed beneath the tail portion 113 of lever 95, the latter being pivoted on a pin 95' mounted above ring 34. Cams 114 and 115 arranged in 50 the same circle on the drum, but axially displaced as regards cams 90 and 91, act to lift push rod 112 to actuate the clamps and cutters, cutting and clamping taking place as the push rod rides off of the cams. The new clamp and cutter as herein provided is operatively spaced beyond fingers 89 and 81 and acts on both of the yarns fed thereby.

While both sets of clamps and cutters are operated each time lever 95 is swung, this is without any disadvantage. The drum is, of course, provided with a suitable cam arrangement to take care of the main station, cams 114 and 115 being for the particular purpose of actuating the new 55 clamp and cutter for the extra yarns at the end of plain knitting in the leg and foot. In the knitting of a high splice heel, for example, both sets of clamps and cutters will be operated, but the set herein added will be without effect if the 60 extra yarns have been thrown out at the start

of the high splice heel. They will be held under clip 107.

The sinker cam ring 26, see Figures 4, 5, 8 and 9, has a pair of openings 116 and 117 formed in its top wall, these openings being behind and 5 slightly beyond the yarn feeding fingers 80 and 81 when the ring is in the position shown in Figure 2, that is, with abutment 30 against post 32. The leading edges of these openings are slightly within the outer contour of the inner guide rib 10 118 of the cam ring, each opening having a straight inner edge and an arcuate outer edge so as to be of segmental shape, as particularly shown in Figure 5. Cams 119 and 120 of segmental cross section are adapted to be projected 15 downwardly in the openings 116 and 117 into the groove 121 followed by the butts 122 of the sinkers or web holders 123 for the purpose of moving the sinkers outwardly. To provide proper clearance the outer wall of groove 121 is recessed at 124 and 20 125, the inner wall of rib 118 being correspondingly relieved at 126 and 127. Between openings 116 and 117 a filler piece 128 is radially grooved to receive a slide 129 whose inner end is beveled 25 as shown.

Cams 119 and 120 have expanded top portions 119' and 120' with flat upper surfaces which lie against the ends of a flat spring strip 130 and are secured thereagainst by means of screws 131 passed through the strip and through plates 132 30 and 133 on the top of the strip. Centrally, strip 130, which is arcuate in plan, Figure 2, is secured to a block 134 from which rises a cylindrical body 135, Figure 9. Strip 130, block 134 and body 135 are bored to provide a cylindrical cavity 136, closed 35 at its upper end, in which is received a vertical post 137 fixed to the cam ring 26. The top of the post is bored and receives a compression spring 138 which bears against the top of body 135 and thus acts to lift cams 119 and 120. The body 135 lies immediately below an adjustable abutment 139 when the cam ring is in the position shown in Figure 2, the abutment 139 being mounted on 40 arm 73 of the yarn feeding mechanism.

An upwardly extending arm 140 is secured to the cam ring radially outwardly of post 137 by means of a screw 141 and at its upper end carries a screw 142 whose head 143 projects over a ledge 144 at the top of block 134. Head 143 is preferably eccentric with respect to the axis of the screw 45 and is held in adjusted position by means of a nut 145. Head 143 cooperates with ledge 144 to limit upward movement of the cams under the force of spring 138 and the lift of the cams may be varied by rotational adjustment of head 143. 50

Opposite slide 129, arm 140 is provided with a recess 146 and with a radial aperture in which is engaged a tubular member 147, the latter having an abutment shoulder at its inner end to hold it against outward movement. A screw 148 is 55 threaded into the outer end of member 147 and is locked in adjusted position by means of a nut 149 threaded thereon. A plunger 150 in the inner end of member 147 is held against slide 129 by means of a compression spring 151 interposed between the slide and the inner end of screw 148.

With cams 119 and 120 in their uppermost position, they are out of the range of the sinker butts so that the sinkers follow substantially their ordinary course. Two groups of sinkers are provided, 70 one group having long butts and the other short butts and when cams 119 and 120 are lowered across the path of the butts and on top of the short butts, flexing spring 130, the on-coming long butts will be diverted outwardly. Cams 119 and 75

- 120 will move further downwardly as spring 130 straightens out and will catch the short butts as they next come around so that as long as the cams remain lowered all of the sinkers will be affected thereby. Slide 129 serves to return the sinkers to their innermost position and its pressure may be suitably adjusted by adjustment of the screw 148. The cams are always within openings 116 and 117 to be properly positioned thereby.
- 10 In Figure 2 reference numeral 152 designates a removable portion in the sinker ring top through which sinkers may be inserted. Opening 116 is partially formed in portion 152 in the spacing arrangement shown.
- 15 With the auxiliary yarn feeding mechanism out of operation, body 135 may freely move beneath abutment 139 as when the needle cylinder is reciprocated. It is always directly under abutment 139 during circular knitting and consequently when 20 the yarn feeding mechanism is lowered, abutment 139 engages body 135 to lower the latter and therewith cams 119 and 120, as in Figure 4. This lowering is affected, as above stated, when the short butt sinkers are beneath the cams. The lower 25 ends of the cams strike the tops of the butts, causing the ends of spring 130 to flex upwardly, the spring straightening out and lowering the cams sufficiently to act on the short butt sinkers as soon as the first long butt sinkers have been 30 cammed outwardly.

In order that the yarn fed by the auxiliary fingers 80 and 81 may be knit, I provide knitting cam mechanisms beneath the fingers respectively, these cam mechanisms being radially movable relative to the needle cylinder and across the line of the needle butts in the cut-out or recess 51, Figure 13. Since the cam mechanisms at each of the auxiliary stations are substantially identical, a specific description of one will suffice. The two 40 mechanisms are designated generally at 153 and 154, Figures 1, 2 and 3. Details of mechanism 154 are shown in Figures 4, 11 and 12 to which reference will now be made.

Reference numeral 155 designates a block secured by means of screws 156 to a plate 155', Figures 2 and 4, which latter is in turn secured to the bed plate 20 adjacent the slope 51' of the cam cylinder by means of screws 156'. Block 155 has a top recess radial to the needle cylinder, and in 50 this recess are slidably a pair of plungers 157 and 158, these plungers being of rectangular cross section between their ends with their top surfaces substantially flush with the top surface of the block. The screws 156 are passed through a 55 cover plate 159 which holds the plungers in position in the block recess so that they are reciprocable in constant paths. Plunger 158 has at its outer end a downwardly projecting lug 160 whose inner face is engaged by a pin 161 disposed in a bore in block 155 and urged outwardly by means 60 of a compression spring 162 so that plunger 158 is constantly urged outwardly.

An angular clip 163 is secured to the outer end of plunger 158 and has a vertical depending flange 65 163' which extends behind plunger 157, the outer end of the latter, as particularly shown in Figure 11, being spaced somewhat from flange 163'. Plunger 157 has a longitudinal bore in its outer end in which is disposed a pin 164 whose outer 70 end bears against flange 163' under the influence of a spring 164' so that plunger 157 is urged inwardly with respect to plunger 158. A screw 165 in the inner end of plunger 158, Figures 4 and 12, has a head which overlies in part the forward 75 end of plunger 157 to limit the action of the

spring pressed pin 164. Screw 165 is held in an adjusted position by means of a set screw 166.

Plungers 157 and 158 at their inner ends have heads 167' and 158' providing top inclined surfaces to which are secured cam plates 167 and 168, respectively, by means of screws, the plates by reason of the inclined supporting surfaces being inclined relative to each other as most clearly shown in Figure 13. From the latter figure it will be noted that the cam 167, which is a lifting cam, extends from substantially the rectilinear bottom of recess 51 to a point above the maximum level of the needle cam cylinder, and cam 168, which is a lowering or stitch cam, extends from above the upper end of cam 167, in spaced relation thereto, to a point spaced from the incline 51'. The inner edges of cam plates 167 and 168 are somewhat rounded in order to follow the contour of the needle cylinder and when closely approached to the latter act to lift 10 and lower all of the needle butts as indicated in Figure 13. The lowering cams lie directly below the fingers 80 and 81, respectively.

Plunger 157 has a downwardly extending lug 25 similar to lug 160 of plunger 158 and into the lower portion of the same is threaded an outwardly extending screw 169, the flange 163' being recessed to provide clearance therefor. A pair of locked nuts 170 on the shank of screw 169 provide abutment means for a purpose to be hereinafter described.

Cam mechanism 153 is exactly the same as mechanism 154 except that due to its position adjacent the leading end of recess 51, its lifting cam 171 is somewhat shorter than cam 167. It is only necessary that the lower edge of this cam be below the crest 50' of the cam cylinder. The lowering cam 172 may be exactly the same as the lowering cam 168. Mechanism 153 further comprises the angle clip 173, the same as clip 163, and the screw 174 with abutment nuts 175, the same as screw 169 and abutment nuts 170.

Journalled in the bed plate 20 slightly in advance of the respective auxiliary knitting mechanisms are a pair of vertical shafts 176 and 177 45 which have reduced portions passed through the plate and extending therebelow. Secured to the lower ends of the reduced shaft portions are collars 178 and 179 which have fixed thereto crank arms 180 and 181 respectively, these extending 50 under the bed plate in substantially parallel relation and having their ends connected by means of a link 182 through crank pins 183 and 184, Figures 1 and 3.

Shaft 176 has secured to its upper end an arm 185 which at its free end carries an adjustable abutment screw 186 which engages the vertical flange of clip 173. Similarly, shaft 177 has secured to its upper end an arm 187 which at its other end carries the adjustable abutment screw 188 which bears against the flange 163' of clip 163.

A link 189, Figure 1, has one end connected to crank arm 180 through pin 183 and its other end connected through a horizontally extending pivot pin 190 with the upper arm 191 of a bell crank lever pivoted on a shaft 192, the other arm 193 of the lever having a foot 193' serving as a follower for cams 194 and 195 on the drum 47. The cams 194 and 195 are in the same vertical plane 70 and, of course, in planes different from those of cams 80, 81 and 116, 115. Cam 194 has at its leading end a step 194', cam 195 having a similar step 195'.

The arrangement is such that as foot 193' rides 75

- up on step 194' shafts 176 and 177 are rocked in a counter-clockwise direction, Figure 2, abutments 186 and 188 forcing inwardly the respective cam mechanisms, the lifting cams being moved through the springs as at 164'. This initial movement of the cam mechanisms takes place as the short butt needles are passing in front thereof and brings the inner edges of the lifting and lowering cams adjacent the end of the butts, but not in engagement therewith. This initial adjustment of the cams is such, however, that when the long butt needles come around they are engaged by the lifting cams and at substantially the same time as the long sinker butts are engaged by the leading sinker cam. At any time after the last of the group of short butt needles has passed cam 167, and before the leading short butt needle has again come around, the pattern drum 47 is advanced to bring the foot 193' on top of cam 194, as shown in Figure 1, so that the consequent further rocking of shafts 176 and 177 brings the cam mechanisms close to the needle cylinder, as indicated in Figure 11, and holds them there, consequently actuating all needles.
- Cams 90 and 194 are so disposed that the throwing in of the auxiliary feeds and sinker cams is properly timed relative to the throwing in of the auxiliary knitting cams so that knitting at the auxiliary stations will be properly initiated and so that all the said auxiliary mechanisms will be thrown out in properly timed relation, cam 114 for the clamp and cutter mechanisms then coming into operation. As before explained, push rod 45 rides on cam 90 during knitting of the stocking leg and foot 193' rides on cam 194 for the same period. Push rod 45 rides on cam 91 during the knitting of stocking foot and the follower 193' rides on cam 195 for the same period, the clamp and cutter cam 115 then coming into play. A tension spring 196 fastened to lever arm 191 and suitably anchored at its other end to a fixed part holds the follower foot down and acts to return shafts 176 and 177 when the follower foot rides off of cam 194 or 195. Upon such return the auxiliary cam mechanisms are similarly moved to inoperative position by the springs as at 162, the plungers as at 158 carrying with them the plungers as at 157 by means of the abutments as at 165.
- The movements of the pattern drum 47 are controlled from the pattern chain in the usual manner and since this control is well understood, it has been thought to be unnecessary to show the specific pattern chain design herein.
- A bracket 197 secured to the edge of bed plate 20 has a horizontal plate portion slightly above the edge of the bed plate to the outer corners of which are pivoted a pair of arms 198 and 199 by means of screws 198' and 199', arm 198 being slightly bent so as to overlie arm 199. The free end of arm 198 lies in front of abutment nuts 170, and the free end of arm 199 lies in front of abutment nuts 175.
- An arcuate lever 200 pivoted beneath the edge of bed plate 20 on a screw 201 has an up-turned end 202 which projects through an aperture 203 of the top plate of bracket 197 inwardly of arms 198 and 199 and at their point of crossing so as to engage both of the arms. The point of engagement of arms 198 and 199 by the end 202 of lever 200 is nearer their pivot points than their points of engagement with the abutment nuts so that outward movement of end 202, whereby the arms 198 and 199 are swung outwardly, is transmitted to the abutment nuts in increased ratio. The

abutment nuts engage the ends of the arms only when the auxiliary knitting cam mechanisms are in their extreme inwardly projected position, as in Figure 2, being otherwise outwardly spaced therefrom.

On the opposite side of the machine from the auxiliary knitting stations, a flat elongated block 204 is secured to the top of the bed plate through longitudinally extending slots 205 by means of screws 206, so that the block is longitudinally adjustable along the bed plate. One end of the block 204 projects beyond the edge of the bed plate and is provided with a rectangular vertical opening 207. At its underside the block 204 is provided with a longitudinally extending recess 207' which runs from the opening 207 to the inner end of the block. In this recess is slidable a plunger 208 which at its inner end bears against a lever 209 pivoted at 210 to the bed plate. The free end of lever 209 abuts the horizontal flange 65' of the segment 65 which carries the right hand stitch cam. A hook 211 at the end of the flange 65' adjacent block 204 is engaged by one end of a tension spring 212 whose other end is anchored to the block. This spring and a compression spring 213 acting on the other end of the segment, normally act to hold the segment in its extreme position of proximity to the needle cylinder with the stitch cam in operative position.

A vertically extending rod 214, Figure 1, has a reduced upper end 215 engaged in opening 207 of block 204. Beneath this reduced portion the rod 214 has a cam surface 216, and below the latter a further cam surface 217. When rod 214 is moved upwardly, the cam surface 216 is adapted to act on the end of plunger 208 to move the same inwardly and thereby throw lever 209 to move segment 65 outwardly against the action of springs 212 and 213 and thereby render the right hand stitch cam inoperative. The end of lever 200 opposite its up-turned portion 202 lies in the path of cam surface 217 when rod 214 is moved upwardly.

It will be noted that the cam surface 216 is spaced a substantial distance below the end of plunger 208, whereas the cam surface 217 is comparatively close to the cooperating end of lever 200. Consequently, a relatively small upward movement of lever 214 will cause surface 217 to engage and swing lever 200 in a counter-clockwise direction, thereby operating arms 198 and 199 to withdraw slightly the auxiliary lifting cams while the lowering cams are still held in their position of extreme inward projection by arms 185 and 187. This slight movement of the lifting cams will cause them to miss the butts of the extra-short butt needles 63 and 64 so that these needles will not doff their stitches. Cam rise 50 does not raise the needles high enough to doff the stitches, and ordinarily the needles are not raised high enough for this purpose until they go up on cam 52. Therefore, when cams 171 and 167 are withdrawn far enough to let the two extra-short butt needles by, these needles do not doff their stitches, and, therefore, form tuck stitches at the two auxiliary stations. The stitches are then doffed when these needles rise on cam 52.

If the rod 214 is projecting further upwardly, lever 200 will not only be swung, but plunger 208 will be moved inwardly so that the right hand stitch cam will be thrown out. This occurs when it is desired to do tuck stitching as in the picot edge in the top of a stocking. Since in this case

the auxiliary stations are inoperative, the movement of lever 200 is without effect.

The lower end of rod 214 is connected through a pin and slot connection with one arm 218 of a substantially horseshoe-shaped lever whose other arm 219, horizontally spaced from arm 218, carries a follower lug 220 above an edge of the pattern chain 48. A link 214a pivoted to rod 214 has a recess in which is engaged the tip of arm 218, a spring 214b pulling downwardly the link and therewith the rod 214. Upward swinging of the lever displaces the link and rod upwardly, as will be understood. The lever 218, 219 has upward extensions as at 221, pierced at their upper ends and pivoted on a horizontal stud 222, the stud 222 being parallel to the axis of the chain sprocket 48'. I have indicated on the chain a pair of cams 223 of a height adapted to raise lever 214 so that lever 200 will be swung, but plunger 208 will remain unaffected, cams 223 being on the side bars of adjacent chain links.

I have also indicated a cam 224 on the chain in line with cams 223 but considerably higher than the latter so as to swing lever 218, 219 through its full range and thus bring cam surface 216 into action. Cam 224 is not necessarily in its proper relation on the pattern chain as shown, being merely indicated for the purpose of demonstrating its comparative height. Each cam 223 will cause two tuck stitches to be made in a single course and between the cams a number of plain courses will be knit and a number of cams 223 are provided so that the desired series of fashion marks will be obtained. By means of well known mechanism link 214a is adapted to be kicked out of engagement with arm 218 at the proper time so that the extra-short butt needles will remain out for only one course, rod 214 being immediately lowered by spring 214b upon release 40 of the latch from the arm. (See U. S. Patent #1,897,081, Page, January 1, 1929.)

The machine operates in the ordinary manner in knitting the turned welt, although, where appropriate, the pattern chain may be provided 45 with a cam 224 to cause tuck stitches to be formed. After the completion of the welt, the auxiliary yarn feeding fingers 80 and 81, the sinker cams 119 and 120, and the knitting cams 171, 172 and 167, 168, are thrown in through 50 the mechanism herein before described and as shown. With the stitch cams 172 and 168 still in, lifting cams 171 and 167 may be periodically slightly withdrawn so that the needles with the extra short butts will pass and will form tuck 55 stitches. The auxiliary knitting mechanisms may be thrown out just before the starting of the heel or before the starting of the high splice heel if one is to be knit. If the foot is to have a reinforced sole, cams 91, 115 and 195 may be 60 omitted so that the auxiliary mechanisms are held out of action until the next stocking is reached. Further drum cams could, of course, be provided to take care of different conditions.

While as mentioned above, the auxiliary feeding stations may be rendered inactive when a splicing yarn is being fed at the main station, they may in some cases be satisfactorily left in action. With two auxiliary stations in action during splicing at the main station, it is evident that the splicing yarn will be present only in every third course. A more satisfactory result is obtainable with the splicing yarn appearing in every other course and for this reason I have provided the arrangement shown in Figures 14 to 18, which enables one of the auxiliary stations to be rendered

inactive while the other remains active during feeding of the splicing yarn at the main station. With this arrangement excellent results are obtainable, particularly when yarns of very fine gauge are being used, the product being substantially indistinguishable from one in which the splicing yarn appears in every course.

According to Figures 14 to 18, the yarn feeding fingers, sinker cams and knitting cams at the auxiliary stations are independently mounted 10 and have independent actuating mechanism. Arcuate bars or blocks 230 and 231 are independently slideable on posts 232, 233 and 234, 235, respectively, the posts being mounted and their appurtenances being the same as in the first 15 embodiment. The bars carry yarn feeding fingers 236 and 237 respectively, these being identical with those hereinbefore described. Bar 230 has an outwardly extending arm 238, and bar 231 an outwardly extending arm 239 substantially parallel to arm 238. The lever 23 hereinafter described extends over bar 231 only. Pin 38, mentioned above as the pivotal support of arm 38, is lengthened into the corresponding pin 240 on the end of which, opposite barrel 32, 25 is mounted a barrel 241, the latter carrying an arm 242 whose free end 243 is above bar 230. An oppositely extending arm 244 on barrel 241 has its free end positioned above a push rod 245 identical with the previously described rod 37 30 and positioned beside the latter for similar guidance. It may here be mentioned that the upper ends of these rods are curved, as shown for example in Figure 14, so that when the latch guard ring 36 is swung upwardly, arms 35 and 244 will 35 ride along the rod ends without interference. The lower end of rod 245 is mounted in a slot of a push rod 246 in exactly the same manner as indicated in Figure 1. The push rod 246 has its upper end guided in an extra slot in the usual comb which guides the upper ends of the usual push rods such as are associated with the yarn feeding fingers at the main station, the lower end of rod 246 being spaced axially of the drum from the lower end of push rod 45. Suitable cam 40 means is arranged on the drum for cooperation with the lower end of push rod 246 to carry out the purposes of the invention.

Arms 230 and 239 carry at their ends adjustable abutment screws 247 and 248, which, during 50 circular knitting lie directly above the bodies or plungers 249 and 250 which may be identical in form and mounting with the body 185 heretofore described. At its lower end plunger 249 carries a flat spring 251, a similar but separate spring 55 252 being carried by plunger 250. At its free end spring 251 carries an auxiliary sinker cam 253, spring 252 similarly carrying a sinker cam 254. The sinker cam ring is the same as hereinbefore described and the sinker cams themselves are exactly the same as those particularly shown in Figures 5, 8 and 9, the only difference being that they are independently movable. With the sinker cam ring in the position which it occupies in rotary knitting, abutment screws 247 and 248 are directly over plungers 249 and 250 respectively. The upper end of arm 140' is laterally expanded and carries two screws 255 and 256 whose eccentric heads overlie lower ledges 257 and 258 of plungers 249 and 250, Figure 16, so that upward movement of the latter is properly limited. Presser 129 remains the same.

The lifting and lowering cams are the same as in the embodiment just described, but are shown in Figures 14 and 15 as being mounted in a single

arcuate block 259 which at its medial portion provides a radial groove in which is slidable the shank of a plunger 260 which has an aperture 261 operatively receiving the up-turned end 202 of the arcuate lever 200. Beyond aperture 261 the plunger 260 carries an arcuate bar 262 whose ends extend behind the abutment nuts 170 and 175. This latter arrangement is somewhat preferred by me to that shown for example in Figure 10 3, since it eliminates some of the friction developed in the use of the cross arms 198 and 199. The operative effect is otherwise the same.

The shafts 176 and 177 have secured to their lower ends arms 263 and 264 respectively, the latter being somewhat longer than the former. 15 A link 265 connects the free end of arm 263 with the upper end of a lever arm 266 pivotal on shaft 192, and a link 267 connects the free end of arm 264 with the upper end of a lever arm 268 mounted beside arm 266 on shaft 192. The extra length of arm 264 enables link 267 to clear arm 263 without interference. Lever arm 268 is of greater length than lever arm 266 so that equal movement of the two will cause equal angular oscillation of 25 arms 263 and 264.

The cam 269 shown in Figure 17, is the same as cam 194, Figure 1, and since it is of a width and shape to engage simultaneously and for the same period the lever arms 266a and 268a, the operation of the auxiliary knitting cams will be the same as before described. However, with a cam such as is shown 270 in Figures 14 and 18 arranged on the drum for coaction with the lever arms, lever arm 268a will pass off into the cut-out 35 270a while lever arm 266a is still riding on cam portion 270b. Shaft 177 will thus be rocked to withdraw the knitting cams at the second auxiliary station, although those at the first station will still remain for a period in active position.

40 When the knitting cams at the second station are thus withdrawn, it is, of course, necessary that the sinker cam at that station be concomitantly withdrawn and the yarn feed interrupted. For this reason the drum cam associated with 45 push rod 45 is shorter than the one associated with push rod 246 so that push rod 45 will lower as the knitting cams at the second station are withdrawn. Arm 83 will immediately be lifted by its spring 83' releasing the bar 231 so that 50 the latter may be lifted by its associated spring to raise finger 237 out of feeding position, plunger 250 simultaneously rising under the influence of its associated spring and thereby lifting sinker cam 254 out of the range of the sinker butts. 55 Push rod 246, however, is still held up and knitting continues at the first auxiliary station. The cam 90 is enough longer than the cam associated with push rod 45 so that the yarn feeding finger and sinker cam at the first auxiliary station will 60 be held downwardly as long as lever arm 266a is on cam portion 270b.

It may be assumed that at the moment arm 266a drops into the cut-out 270a and the yarn feeding finger and sinker cam at the second station simultaneously elevated, a splicing yarn is being introduced, or is about to be introduced, in the well-known manner at the main station for a high splice heel. Since the first auxiliary station knits a course on top of the spliced course 70 and since no splicing yarn is introduced at the auxiliary station, a plain course will exist between the courses in which the splicing yarn is introduced at the main station. The resultant fabric is as indicated in Figure 19, reference character 75 x designating the yarn fed at the first auxiliary

station, m that fed at the main station and s the splicing yarn. When the high splice heel has been completed in this manner, arm 266a and push rod 246 drop and the knitting of the heel pocket is begun. The auxiliary clamp and cutter 5 act as before.

By supplying a suitable cam for push rod 246 and a cam of the width of portion 270b for lever arm 266a, the first auxiliary station may be thrown in at the commencement of the knitting 10 of the foot and a reinforced foot fabric the same as that shown in Figure 19 may be produced, the second auxiliary station remaining inactive. In Figure 14, however, I have shown the same cams 91 and 195 as in Figure 1, so that both auxiliary 15 stations are thrown in concomitantly while the foot is being knit. During this period a splicing yarn may be fed at the main station, but in this case will appear only in every third course, as 20 will be understood.

I wish to repeat that while the invention has been described with reference to a rotary cylinder stocking knitting machine of particular type, it is not limited in its application to this particular type of machine nor to the tubular article to be 25 knit. In view of permissible changes in the form and arrangement of parts, it is to be understood that the invention is not limited except as in the following claims.

I claim:

1. The combination with a circular knitting machine having a needle cylinder with groups of needles having butts of different length, and a main knitting station with yarn feeding means and knitting cam mechanisms, of a plurality of auxiliary knitting stations spaced apart and from said main knitting station circumferentially of said cylinder, yarn feeding mechanisms at said auxiliary stations respectively, needle lifting and lowering cams at each of said auxiliary stations, 40 means for imparting simultaneous movement to said lifting and lowering cams at the auxiliary stations from a normally retracted position and toward said cylinder across the line of the needle butts, said movement comprising an initial step 45 wherein said lifting and lowering cams are approached to a position close to the ends of the shorter needle butts so that the butts of the longer butt needles may engage the lifting cams, said movement comprising a final step wherein 50 the lifting and lowering cams are approached to a position close to the cylinder so as to be engaged by the shorter needle butts when the latter come around, means for simultaneously operating the yarn feeding means at the auxiliary stations, 55 said auxiliary stations when active being adapted to knit a corresponding number of courses in addition to the course knit at the main station, said lifting and lowering cams being returnable to inactive position subsequent to a knitting operation, and means for slightly withdrawing said lifting cams out of the range of some of the butts while the lowering cams remain in position close to the cylinder.

2. The combination with a circular hosiery knitting machine having a needle cylinder and a main knitting station with yarn feeding means and knitting cam mechanisms, of a plurality of auxiliary knitting stations with yarn feeding means 70 and knitting cam mechanisms at each of the same, means for concomitantly throwing in or out the feeding means and cam mechanisms at all the auxiliary stations, and means for throwing in or out said means and mechanisms at one 75

of the auxiliary stations independently of those at another auxiliary station.

3. The combination with a circular hosiery knitting machine having a needle cylinder, a sinker ring, and a main knitting station with yarn feeding means, knitting cam mechanisms, and a sinker cam, of a plurality of auxiliary knitting stations each having yarn feeding means, knitting cam mechanisms and a sinker cam; means for con-
5 comitantly throwing in or out the feeding means,
10 the cam mechanisms and the sinker cam at all the auxiliary stations; and means for throwing in or out said feeding means, knitting cam mechanisms and sinker cam at one of the auxiliary sta-

tions independently of those at another auxiliary station.

4. The combination with a circular hosiery knitting machine having a needle cylinder and a main knitting station with main yarn feeding 5 means, yarn feeding means for a splicing yarn, and knitting cam mechanisms, of a plurality of auxiliary knitting stations each having yarn feeding means and knitting cam mechanisms, means for rendering all the auxiliary stations active during leg knitting, and means for rendering all except one auxiliary station inactive during feed 10 of the splicing yarn at the main station.

EDWARD H. STEERE.
